Primary Examiner — Bao-Yen T Nguyen*Assistant Examiner* — Jessica Ruth Grable(74) *Attorney, Agent, or Firm* — Simpson & Simpson, PLLC(57) **CLAIM**

The ornamental design for a module shelf, as shown and described.

DESCRIPTION

FIG. 1 is a top perspective view of a module shelf of the present invention;

FIG. 2 is a front elevation view of the module shelf shown in FIG. 1;

FIG. 3 is a rear elevation view of the module shelf shown in FIG. 1;

FIG. 4 is a left side elevation view of the module shelf shown in FIG. 1;

FIG. 5 is a right side elevation view of the module shelf shown in FIG. 1;

FIG. 6 is a top plan view of the module shelf shown in FIG. 1; and,

FIG. 7 is a bottom plan view of the module shelf shown in FIG. 1.

(Continued)

The drawings illustrate a module shelf as shown in the drawings.
